LINER

Oliver B. Andrews, Chattanooga, Tenn.

Original application November 9, 1935, Serial No. 49,009. Divided and this application November 16, 1936, Serial No. 111,062

4 Claims. (Cl. 217—3)

This invention relates to liners, and more particularly to a liner adapted to fit on the inside of a container such as a fruit basket to protect the contents from injury resulting from contact with the rough walls of the basket.

The present invention contemplates the provision of a liner formed from a strip of paperboard material having its ends permanently secured together to form an endless wall of sufficient strength to support a column of fruit equal to the amount necessary to fill a basket, and having a weakened portion or portions which permit the liner to break and yield outwardly when the basket is shaken or the cover secured to the basket, or the like. The weakened portions preferably comprise a line or lines of weakening extending longitudinally of the liner but not continuous throughout the entire length of the liner.

According to the present invention the weakened portions preferably are so disposed that the liner may break throughout its entire length, but not continuously, and hence the liner does not completely separate but always retains its endless nature. The weakened portions preferably are so disposed that the liner breaks along only short lines whereby only a small area of the basket wall could possibly be in contact with the fruit. In other words, the weakened portions are distributed to permit only sufficient breaking of the liner to relieve the pressure and without exposing any substantial area of the fruit to contact with the basket walls.

An object of this invention is to provide a liner for baskets or other containers adapted to contain fruit, vegetables or similar articles, which liner is adapted to break under abnormal pressure only sufficiently to relieve such abnormal pressure and without exposing any substantial portion of the fruit to engagement with the basket walls.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which

Fig. 1 is a plan view of a blank used in forming a basket liner according to the present invention;

Fig. 2 is a perspective view of a completed liner

in set-up position;

Fig. 4 is a perspective view of a basket of fruit with cover attached and liner inserted, a portion of the basket and cover being broken away to illustrate the liner in position in the basket;

Figs. 5 to 7 are plan views respectively of three different modified forms of liners constructed according to the teachings of the present invention;

Fig. 8 is an enlarged fragmentary view showing a cross-section taken longitudinally along a portion of the line of weakening 3, shown in Fig. 1;

Fig. 9 is a view similar to Fig. 8 showing a modified form of weakening arrangement;

Fig. 10 is a view similar to Fig. 8 showing another modified form of weakening arrangement; and

Fig. 11 is an enlarged fragmentary view showing a cross-section taken transversely of still another modified form of weakening arrangement.

Referring to Fig. 1, a liner blank 1 is cut from a sheet of paperboard of the desired quality and tensile strength, and is provided with a plurality of spaced breathing apertures 2.

The blank 1 is provided with one or more lines 3 of perforations extending from its end edge 6 inwardly, and a line 4 of perforations extending inwardly from the other end edge 7 of the blank 1. The lines 3 and 4 terminate inwardly short of the edges 6 and 7 respectively and preferably centrally of the blank 1. Preferably the lines 3 and 4 extend at least to the center of the blank and they may overlap longitudinally; however, in some cases these lines do not extend all the way to the center.

The liner is completed by lapping the side edge 11 over the side edge 10 and adhesively securing the edge portions together, as shown in Fig. 2, to form an endless wall or collar structure having the general form of a truncated cone, and constituting the completed liner 9.

If desired, the perforated lines 3 may be diametrically opposite and may provide natural fold lines whereby the liner may be collapsed for the purpose of shipment or easy handling. However, if desired, the liner 9 may be provided with score lines 5 along the lines 3 and 4 and in continuation thereof to facilitate collapse of the liner into substantially flat condition.

The liner blank may be cut to shape, or punched to provide the apertures 2, perforated to provide the lines of perforations 3 and 4 and scored for folding purposes automatically on a

cutting and scoring machine in a single operation. Gluing of the side portions 10 and 11 of the liner blank can also be performed automatically on a suitable automatic gluer.

The completed fruit package which is assembled by the well-known inverted packing method, is illustrated in Fig. 4, and comprises a basket 12 in which the liner 9 is disposed and lies against the walls of the basket surrounding the articles of fruit 13, and a cover 14, secured on the basket 12 to retain the fruit therein.

When the basket has been packed in the manner above described, any abnormal pressure developed in the body of fruit, owing either to the shaking during packing or the pressure developed when the cover is applied, will cause the liner to break outwardly along one or more of the perforated lines 3 and 4, thereby relieving the fruit from this abnormal pressure. In Fig. 4 there is illustrated the condition wherein the fruit 13 in the bottom portion of the basket has caused the liner 9 to break along the perforated line 4, and thus causes the adjacent edge portions 17 and 18 to separate and expand outwardly. In a similar manner, the condition is shown wherein the fruit has caused the upper portion of the liner to break along the line 3 and the edge portions 15 and 16 are separated. It will be understood that the liner may break along either of lines 3 or 4 or all of them depending upon the pressure of the fruit. In Fig. 4, the condition of the liner has been somewhat exaggerated for the sake of illustration.

Should the liner 9 be too large for the basket 12, the liner 9 will generally break along the perforated line 3 or 4 or both, and the portions adjacent the break will overlap to adjust the liner 9 to the size of the basket 12 and contained fruit 13. The portion beyond the ends of the lines 3 and 4 does not break, but constitutes a continuous, unbroken belt which prevents the liner as a whole from separating and spreading.

It should be understood that where the basket and contained fruit are slightly larger than the liner throughout substantially its entire length, the edges 17, 18, 15 and 16 and the corresponding edges adjacent lines 6 and 7 all will expand outwardly; however, owing to the fact that the continuous belt does not break, the liner will not separate entirely, and thus will prevent the fruit from coming in contact with the inner wall of the basket throughout any substantial area.

Preferably, in accordance with the present invention, the liner 9 is formed of sufficiently tough material so that the breaking of the liner 9 caused by abnormal pressure from within will be localized in and confined to the predetermined lines of breakage 3 and 4, and the liner 9 will not break at any other points. Also, the continuous belt is of such length that it will not break but will twist and bend to permit adjustment of the fruit within the basket. The material from which the liner is constructed, preferably, is sufficiently pliant and flexible to permit ready adjusting movement of the fruit within the liner to prevent bruising or crushing of the fruit. However, the material is of sufficient stiffness to prevent appreciable curling or fraying of the end edges of the liner, and more particularly fraying and curling of the edges adjacent the lines of breakage.

The provision of a considerable number of lines of weakening permits the liner to separate only a small amount at each point of abnormal pressure, and thus only a relatively small area of the

fruit can come into direct contact with the walls of the basket. Thus, the amount of abrasion of the fruit caused by direct contact between the fruit and the basket is substantially eliminated or at worst confined to a relatively small area and a relatively small number of separate pieces of fruit.

As pointed out above, the unperforated belt portion of the liner between the lines of weakening 3 and 4 and the edges of the liner is of sufficient length and strength to resist breaking when the lines of weakening are broken out due to abnormal pressure. In order to insure that the breakage will be confined to the lines of perforations and that the liner will not tear beyond these lines of breakage, short transverse lines of perforations may be provided at the interior ends of the lines of weakening.

A construction of this type is shown in Fig. 5, wherein a blank 40 is provided with the usual ventilating openings 41 and with spaced lines of perforations 42 and 45, arranged in staggered relation and extending from opposite end edges through a substantial distance along the length of the liner and beyond the central circumference. The lines 42 which extend inwardly from the lowermost end edge (as shown in Fig. 5) may be intersected at its interior end by a short transverse line of perforations 43. The line or lines 45 intermediate the lines 42 extend inwardly from the opposite end edge, and may be likewise intersected by the transverse, perforated lines 46. If desired, score lines 44 and 49 may be provided in prolongation of lines of perforations 42 and/or 45 to permit bending of the blank along these lines. However, such score lines may not be necessary where the lines of perforations extend into the blank a substantial distance, as the perforations provide natural fold lines.

In the construction illustrated in Fig. 6, a blank 50 is provided with ventilating openings 51 and an echelon series of lines of weakening 52, 54 and 55 spaced at equal intervals across the blank. The line 52 extends inwardly from one end edge of the blank to a point approximately centrally of the liner. The line 54 extends from a point spaced inwardly from one end edge approximately one-quarter the length of the liner to another point spaced inwardly a distance approximately one-quarter the length of the blank from the other end edge of the blank. The third line 55 begins at the end edge of the blank opposite to the edge intersected by the line 52, and terminates midway of the liner. The perforated lines 52, 54 and 55 may be shorter or longer than above specified, depending upon the material used, the basket irregularities and other conditions. If desired, score lines 53 and 56 may be provided in prolongation of lines 52 and 55, respectively, to provide fold lines.

It will be understood that it is generally desirable to provide, in the liner blank, spaced apertures or openings distributed substantially equally along the liner, for the purpose of permitting circulation of air through the fruit basket. Such openings may be employed in connection with the lines of perforations, as illustrated in Fig. 7.

A blank 80 is provided with an arcuate row of ventilating openings 81 spaced from one end edge and a similar row of perforations 82 spaced from the other end edge. An echelon series of lines of weakening 83, 84 and 85 may be provided, the lines 83 extending from one end edge to one of the openings 81, the line of weakening 84 extending from the adjacent opening 81 to the ad-

5 jacent openings 82 of the other row of perforations, and the line 85 extending from the next adjacent perforation 82 to the corresponding end edge of the liner. This pattern of lines of weakening is repeated to provide echelon series of lines of weakening.

10 It will be understood that, instead of providing transverse lines of weakening and ventilating openings adjacent ends of the lines of weakening, it is possible to provide reinforcing of the liner at the ends of the lines of weakening. Thus, instead of providing additional weakening of the liner, as has been disclosed above, patches or staples or analogous reinforcing means may be 15 applied to the liner at the critical points to provide against undesired tearing of the liner.

20 The lines of weakening in the several forms of liners herein disclosed may be formed in various ways. For example, it may be constituted by substantially rectangular open slot-like perforations 90 extending all the way through the liner and spaced apart by a wall portion 91 (Fig. 8). In Fig. 9 a somewhat stronger construction is 25 illustrated wherein the line comprises punched or cut indentations 92 which extend only partially through the liner and are spaced apart by wall portions 93. In Fig. 10 there is illustrated a line of weakening constituted by closely spaced cone-shaped depressions or indentations 94 extending substantially, but not entirely, through the liner and separated by wall portions 95. In Fig. 11 the line of weakening is illustrated as 30 formed by a deep, continuous, longitudinally extending groove or score 96 which compresses and displaces the material as indicated at 97.

35 This application is a division of my copending application, Serial No. 49,009, filed November 9, 1935.

What is claimed is:

40 1. A basket liner for packing fruit and the like comprising an endless wall of sufficient strength to support a column of fruit and having weakened portions extending inwardly from the top and bottom edges thereof alternately and at least to the center of the liner, whereby to per-

mit breaking under predetermined excess pressure, each of said lines of weakening extending only partly throughout the height of the collar, whereby the unweakened portion of the liner includes a tortuous, continuous band of sufficient 5 strength to confine said breaking to said lines of weakening, and permitting expansion of said lines at both top and bottom without complete severing of the liner.

2. A basket liner for packing fruit comprising 10 an endless wall of sufficient strength to support a column of fruit and having staggered overlapping lines of weakening permitting said liner to break upon predetermined excess pressure, certain of said lines of weakening extending inwardly from 15 the top and bottom edges respectively of said liner, said lines together extending throughout substantially the height of said liner, said liner being of sufficient strength to confine said breakage to said staggered lines of weakening, whereby 20 the liner is capable of substantial expansion throughout substantially its entire height without complete severing of the liner.

3. A basket liner for packing fruit and the like including a collar having sufficient strength to 25 support a column of fruit and having a plurality of score lines permitting said collar to be folded, said collar having lines of weakness extending partially along said fold lines and an additional line of weakness intermediate said fold lines and 30 the ends of the liner, said lines of weakness permitting said liner to break upon predetermined excess pressure but said liner being formed of material of sufficient strength to confine said breakage to said lines of weakness.

35 4. A basket liner for packing fruit including an endless collar of sheet material having sufficient strength to support a column of fruit and having spaced lines of weakening extending inwardly from opposite end edges of said liner and terminating intermediate the end edges of said liner, said liner having also a line of weakness intermediate said first named lines and terminating inwardly short of both of said end edges.
